INSULATING JACKET

Peter Schlumbohm, 41 Murray St., New York, N.Y.

Filed July 20, 1959, Ser. No. 56,856

Term of patent 14 years

(Cl. D44—10)

Fig. 2 is an elevational view of one of the halves thereof.

I claim:

The ornamental design for an insulating jacket, as shown and described.
